UNITED STATES PATENT OFFICE

ALBERT ERNEST, OF CHICAGO, ILLINOIS

FURNITURE

Application filed December 5, 1929. Serial No. 411,915.

This invention relates in general to furniture, and more particularly to improvements in cushioned seats, such as chairs, davenport, sofas and the like, and, while the invention is illustrated and described as applied to an article of furniture commonly known as a davenport, it will be understood that the invention is useful in other analogous articles of furniture, and, therefore, finds a wide field of utility.

Those skilled in the art to which the invention pertains will understand that in the ordinary common construction of davenport, cushioned chairs and the like, there is provided an underframe with arm rests and a back, and this frame is usually supported on legs at a desired height from the floor. Within this frame is supported a spring-containing structure which extends usually not more than the depth of the frame, and upon the spring structure thus provided there are placed one or more cushions which may also contain springs, and, in many instances, are made in sections so that essentially two spring structures are included in the complete article of furniture, that is, in the seating portion thereof. This construction requires the provision of a fixed spring structure in the underframe and also a fabric covering for this spring structure which, as well known to those skilled in the art, is prone to collect dust and dirt, and that it is practically impossible to clean this part of the furniture.

The principal objects of this invention are to provide an article of furniture of the character referred to wherein the cushions themselves contain the sole spring seat structure of the furniture, that is, the cushions are removable but are increased in depth and are supported by the underframe, there being no intermediate spring structure provided. In this manner the cushions, containing the entire spring structure and being supported on a webbing or steel straps which are attached to the top of the underframe, may be readily removed for airing or cleaning. This invention further eliminates the recess usually present along the ends at the arm rests and at the back of the davenport, in

which dust and dirt can collect. When the cushions are removed it exposes the under strap or webbing structure and permits of the application of a vacuum cleaner or other sweeping means directly to the webbing so that there is no opportunity for any dust or dirt to lodge in the seat cushions for any appreciable time, thus making the device more sanitary than the devices now on the market known to me.

Further objects of this invention reside in the provision of an improved arrangement and mounting of the supporting straps on the underframe of the article of furniture; the provision of an improved spring structure for the individual cushion or seat member; the provision of improved tying means for the spring members of the article of furniture; and the provision in general of an article of furniture of the character referred to in which the construction is considerably simplified and in which the cost of production may, therefore, be materially reduced.

The foregoing and such other objects and advantages as may appear or be pointed out as this description proceeds are attained in the structural embodiment in which:

Figure 1 is an elevational view of an article of furniture constructed in accordance with this invention;

Figure 2 is an end elevational view of the same partly broken away to show the under construction;

Figure 3 is a fragmentary sectional view showing a detail of the construction shown in Figure 2;

Figure 4 is a top plan of the structure shown in Figure 3;

Figure 5 is a plan view, partly in elevation and partly in section, of one of the seat cushions;

Figure 6 is a sectional view on the line 6-6, part being shown in elevation, looking in the direction indicated by the arrows;

Figure 7 is an enlarged detail view of a part of the seat cushion construction;

Figure 8 is an enlarged elevational view of the spring tying element;

Figure 9 is a sectional view taken on the 100

line 9-9 of Figure 8 looking in the direction indicated by the arrows;

Figure 10 is a view similar to Figure 8 of another form of the spring tying means, and

5 Figure 11 is a sectional view, taken on the line 11-11 of Figure 10, looking in the direction indicated by the arrows.

Referring now more particularly to the drawings, and first to Figures 1 to 4 all inclusive, I have illustrated a davenport but it will be understood, of course, that this structure to be described may be equally applicable to a cushioned chair or a similar article of furniture.

15 The davenport comprises an underframe 5 mounted on front legs 6, 6, the rear legs 7 supporting the underframe at the back of the article of furniture and usually extending up into the back rest 8 which is of the usually
20 so-called "overstuffed" type or may be of any other construction. At the ends of the davenport there are provided arm rests 9 and 10 joined with the back rest 8 and built up in overstuffed fashion on the underframe.

25 The underframe 5 usually comprises a front rail 11 and rear rail 12 and end rails 13, only one of the latter appearing in the drawings. It is customary, also, to provide intermediate transverse rails 14 and 15, as shown in Figure 1.

18 as packed onto said edge over a portion of the 19 in Figures 20 and 21. This 20 setting spans the open spaces between the 21 front and rear rails and the intermediate.

rails and thus forms a yielding supporting structure. The netting is covered on its top by a fabric top lining; 20 twillings blind.

"tacked" is indicated at 21 on the front rail, 22 having its inner edge 23 tacked with the lining 20 after having been laid.

with the lining 20 after having been blind stitched, as indicated at 24, beneath the front of the blind stitched edge of the collar 22, there may be

tacked a facing fabric 25 and in the roll 22, there is provided a filler of cotton or the like 26, and, similarly, a filler 27 in the facing 25.

In some articles of furniture, the facing is omitted where the front rail is exposed, and is carved with a desired design. The rear rail

edges of the bottom and top linings 18 and 20 and the webbing or netting strips 16 and 17 are suitably tacked to the top surface of the rear rail 12, and as this structure is hidden beneath the fabric outer covering 8a of the back rest member 8 and by the complementary coverings of the arm rests, the netting or webbing and linings may be tacked in any desired manner, and this part of the structure is, therefore, not shown. It is only necessary to state that it is important, however, that the netting and the linings be supported from the upper edges of the end and rear rails.

This yielding netting forms a support for one or more seat cushions, indicated generally at 29, 30 and 31, and these cushions extend from the top of the underframe to a point near the top of the arm rest or, as shown in the drawings, at least to the point at which the arm rest flares in the particular design shown. Said cushions also are conveniently of a depth substantially equal to the height of the top of the supporting frame from the floor. In other words, the depth of the removable cushions is substantially one-half of the total height of the seat. This increased depth of the removable cushions makes them equivalent in spring capacity to the combined cushion and frame springs of the prior art.

The cushions all contain spring-structures, which will presently be described, and thus contain the sole spring seating structure of the article of furniture.

As the spring cushions are all substantially identical in construction, but one of the same will be described.

Referring now to Figures 5 to 14, I will provide a cushion structure including an outer case 22 generally designated 32, and an internal spring structure generally designated 33.

The spring structure 33 comprises a pair of substantially rectangular wire frames which may be designated as top and bottom frames 34 and 35 respectively, though it will be understood that the cushions may be upholstered so as to be reversible.

The top frame 34 is shown in Figure 5.

sq 1151 and 1152, and the remaining frame members 34 and 35 confine the group of spring members indicated at 36. These spring members are prefer- 115

erable to the double-cong type, that is, their convolutions are smaller at their medial portions than at their ends. The outermost convolution of each sprung member, indicated in

Figure 6 at 37 and 38, is in each instance tied to the supplemental convolution of an

adjacent spring member, and, where adjacent to the frame members 34 and 35, these outermost convolutions are also tied to the frame

member. For this purpose I provide metal dieclips 39 and 45, the clips 39 being of slightly different shape than the clips 45

The clips 39 are best shown in Figure 9 and comprise body portions 41 having opposed

series of lugs 42 arranged so that when the clip is applied to the adjacent convolutions 37 of adjacent spring members and are bent toward each other, said convolutions will be drawn into the clip and held against accidental displacement. For this purpose, there are two lugs provided on one of the margins of the clip and three lugs on the opposing margin so that an interlocking of the lugs in effect takes place. It is understood that in this form of the clip shown in Figures 8 and 9, the body 41 has oppositely curved margins 43 and 44 which facilitate the engagement of the lugs with the convolutions of the adjacent spring members and does not, when the clip is compressed, that is, when the lugs are bent over, tend to distort the springs.

Where the convolutions 37 or 38 of the springs are tied to the frame members 34 or 35, I provide a clip of a modified construction, indicated at 45, this clip having one straight edge 46 carrying lugs 47 for engagement with the frame 34, and a curved edge 48 having lugs 49 for engagement with the adjacent convolution 37 of the spring member. When the lugs are bent over, the spring member is prevented from disengagement from its proper relationship with the frame, the lugs being arranged so that they form an interlocking engagement in effect similar to the lugs in Figures 8 and 9.

The spring structure thus assembled is then enclosed in a fabric envelope 50 which may be burlap or any other suitable fabric, and this envelope is tied to the frame member by suitable stitching, such as heavy twine or the like, indicated at 51 in Figure 5. In order to place the spring members under partial compression, I provide flexible members of heavy twine, indicated at 52 in Figures 5 and 6, which is attached to the opposite top and bottom walls of the envelope 50.

After the envelope is applied to the spring structure, I then upholster the same to form the complete cushion by applying thereto a filler 53 of cotton, or the like, and then a fabric outer covering 54 of any desired design, the top and bottom peripheral edges of the cover 54 being provided with beads 55 and 56. The construction of the beads 55 and 56 is best illustrated in Figure 7. A roll 58 of the desired color or nature, which is to make up the final outside upholstering, is provided and contains a filler 59 of cotton or the like. The roll 58 is placed about the cotton and stitched, as indicated at 60, to form a pair of tabs 61, and the outer covering 62 of the cushion is blind stitched, as indicated at 63, so that when the covering is completely assembled, the stitching is hidden by the outer covering of the cushion.

The present invention makes it possible to remove entirely the spring structure which, in previous structures of this character known to me, act as dust collectors and eventually

necessitate the complete opening of the spring structure in the bottom of the article of furniture in order to properly clean it. In the present invention the cushions may be periodically removed and placed out doors for airing, and the bottom netting or webbing of the article of furniture may be readily and quickly cleaned of any dust accumulating thereon.

Where I employ the expressions "netting" or "webbing" in the claims it is to be understood that these expressions are interchangeable and either a metallic netting or a fabric webbing may be employed as desired.

Having thus described my invention and illustrated its use, what I claim as new and desire to secure by Letters Patent is:

1. In furniture, in combination, a substantially horizontal underframe comprising front, end and rear rails forming a structure adapted to be supported at a predetermined height above the floor, a netting secured to the top surfaces of said rails and extending across the underframe at substantially the same height as said top surfaces and provided with a retaining roll, and a removable spring filled cushion member supported on said rails and netting and retained by said retaining roll, said cushion being of a depth substantially equal to the height of said underframe from the floor.

2. In a davenport structure, in combination, a substantially horizontal underframe comprising spaced front, end and rear rails, means supporting said underframe, a back and end rests supported on said underframe, a netting secured to and overlying the top surfaces of said rails and spanning the space therebetween to form a substantially horizontal seat support and removable seat members supported by said netting and of a depth substantially equal to the height of the top of said underframe from the floor.

3. In a davenport, in combination, a substantially horizontal underframe comprising spaced front, end and rear rails, means supporting said underframe, a back and end rests supported on said underframe, a netting secured to and overlying the top surfaces of said rails and spanning the space therebetween to form a substantially horizontal seat support and removable seat members supported by said netting and of a depth substantially equal to the height of the top of said underframe from the floor and spring members within and extending substantially the entire depth of said seat members.

4. In furniture, a frame comprising spaced side and end rails, a netting spanning the space between said rails, a bottom lining secured to the top of one of said rails beneath said netting, a fabric roll blind tacked to the top of said rail and extending to said netting, and a top lining over said netting, and blind tacked, together with the inner edge of said

fabric roll, adjacent to the rear edge of said rail.

5. In furniture, having removable seat cushions, a frame comprising spaced side and end rails, a netting spanning the space between said rails, a bottom lining secured to the top of one of said rails beneath said netting, a fabric roll blind tacked to the top of said rail and extending to said netting, and
- 10 a top lining over said webbing and blind tacked, together with the inner edge of said fabric roll adjacent to the rear edge of said roll, said webbing and frame forming the sole support for said seat cushions.
- 15 In testimony whereof, I have hereunto signed my name.

ALBERT ERNEST.
